ATTORNEY.

UNITED STATES PATENT OFFICE

2,277,088

ADVERTISING STRAPHANGER

Viktor Ehrenhaft, Prague, Bohemia

Application July 23, 1940, Serial No. 347,018
In Germany August 7, 1939

3 Claims. (Cl. 40—130)

The present invention relates to a grip device for use in tram-cars, motor busses, subways and the like, the gripping yoke part of which, according to the invention, is connected to an advertising device comprising translucent and replaceable advertising disks or ribbons and whose sources of light are switched on by means of the gripping yoke. Pulling on the said gripping yoke will operate the switch, and the pull having stopped, the sources of light are switched off by fitted-in springs.

Where the feed to the said illuminated advertising device of the power current at disposal within the vehicle, is to be avoided, a replaceable dry cell battery or storage battery may be fitted within the advertising device.

Instead of fixed advertising disks, translucent advertising ribbons or films may be arranged to travel within the said device.

In the drawing, a preferred embodiment of the invention is represented by way of example,

Fig. 1 showing a perspective view of the gripping support according to the invention;

Fig. 2 is a front view of the same, the front advertising plate being removed for the sake of clarity;

Fig. 3 is a side view of a section of the gripping support, and

Fig. 4 shows the connection of the upper portion, which serves advertising purposes, and the handle or support proper comprising a switch fitted in between the two portions.

Referring more particularly to the drawing, the advertising strap hanger of the invention comprises an upper metal frame generally indicated at 10 and a handle or grip 11. Grip 11 is mounted to reciprocate a certain distance in the vertical direction, as will be explained hereinafter. Upper frame 10 is provided with two advertising plates 12 and 13 which are preferably transparent and bear advertising inscriptions or pictures. A plurality of light sources or incandescent lamps 14 are arranged in the interior of frame 10. Electric storage battery 15 is supported by horizontal strip 16. Strip 16 is provided with a flange 17 passed through a slot in frame 10. By means of flange 17 strip 16 may be pulled out to exchange storage battery 15.

One pole of electric battery 15 is connected by means of cable 18 with metal frame 10 and, hence, is in electric contact with incandescent lamps 14. The other pole of battery 15 is connected by cable 20 with a single pole switch shown in Fig. 4. Cable 20 connects dry battery 15 with the upper contact 21 of the switch. Sta-

tionsary contact 22 is connected with cable 23 which in turn connects bulbs 14 in series and with the metal frame 10 of the advertising device.

Upper frame 10 has a loop 25 by means of which it may be supported on the ceiling, for instance, of a railroad car. Spring 26 is interposed between U-shaped portion 27 on grip 11 and a similar U-shaped portion 28 of frame 10. When grip 11 is pulled down, spring 8 is compressed and contacts 21 and 22 touch each other, thus closing the electric circuit, whereupon bulbs 14 flash up and the advertising matter on plate 12 and 13 is illuminated. When grip 11 is released, contacts 21 and 22 are separated again due to the action of spring 26 and the electric circuit is interrupted.

It is, of course, feasible to connect electric bulbs 14 with a main current source instead of a dry battery.

What I claim is:

1. An advertising strap hanger comprising a frame having an upper stationary section and a lower section formed with a loop and slidably mounted in said upper frame section, a spring interposed between said upper and said lower frame section for normally spacing them apart, translucent advertising plates removably secured to the surfaces of said upper frame section, a plurality of electric light bulbs in said upper frame section, an electric circuit including a current source, said bulbs and a switch including a stationary contact in said upper frame section and a movable contact in said lower frame section, whereby when said lower frame section is pulled downwards said switch is closed and said light bulbs are energized.

2. An advertising strap hanger comprising a frame having an upper stationary section and a lower section formed with a loop and slidably mounted in said upper frame section, a spring interposed between said upper and said lower frame section for normally spacing them apart, translucent advertising plates removably secured to the surfaces of said upper frame section, a plurality of electric light bulbs in said upper frame section, a dry battery in said upper frame section, an electric circuit including said dry battery, said bulbs and a switch having a stationary contact in said upper frame section and a movable contact in said lower frame section, whereby a downward pull of said lower frame section closes said switch and energizes said light bulbs.

3. An advertising strap hanger comprising a frame having an upper stationary section and a lower section formed with a grip, said upper

frame section and said lower frame section having each a U-shaped end portion, said two U-shaped end portions being arranged in nested relationship, a spring interposed between said U-shaped end portions for normally spacing them apart, translucent advertising plates removably secured to the surfaces of said upper frame section, a plurality of electric light bulbs spaced in said upper frame section, a dry battery in said

upper frame section, an electric circuit including said dry battery, said light bulbs and a switch comprising a stationary contact on the U-shaped end portion of said upper frame section and a movable contact on the U-shaped end portion of said lower frame section, whereby when a pull is exerted on said grip said contacts are closed to energize said light bulbs.

VIKTOR EHRENHAFT.
